SUPERHETERODYNE RECEIVER

Arne Schleimann Jensen, Emporium, Pa., assignor to Hygrade Sylvania Corporation, Salem, Mass., a corporation of Massachusetts

Application June 24, 1938, Serial No. 215,538

1 Claim. (Cl. 250—20)

This invention relates to frequency converters and more especially to frequency conversion methods and apparatus for use in superheterodyne wave signaling systems and the like.

5 In the usual form of superheterodyne receiver, the intermediate frequency is fixed by the frequency difference between the received signal frequency and the frequency of a local source of oscillations. Since the intermediate frequency is usually constant over the various frequency bands of the receiver, the difference between the received signal frequency and the oscillator frequency expressed in terms of per cent of signal frequency, decreases as the signal frequency increases.

10 For example, assuming a received signal frequency of 3000 kc./sec. and assuming the local oscillator frequency is chosen from the lower side of the signal frequency e. g. 2550 kc., then the frequency difference 450 kc./sec. is 15% of the signal frequency. If the signal frequency is of a higher order, e. g. 30,000 kc./sec., then the local oscillator frequency would be 29,550 kc., and the frequency difference (450 kc.) would be only 1.5% of the signal frequency. It is evident therefore, that the tendency for "pulling" and "interlocking" between the signal and the local oscillator in these usual arrangements increase with increasing signal frequency, and at ultra high frequency these tendencies give rise to serious difficulties. In fact, where an ultra high frequency superheterodyne receiver is to be a practical device, it is necessary to use a correspondingly high intermediate frequency. Not only does this seriously limit the working band of the receiver, but also introduces new difficulties e. g. in the intermediate frequency amplifier and associated equipment.

15 Consequently, it is a principal object of the present invention to provide methods and apparatus whereby the tendency of "pulling" or "interlocking" between the signal frequency and the local oscillator of a superheterodyne radio receiver is reduced, while allowing the receiver to be used over a wide range of wave bands.

20 Another object is to provide methods and apparatus whereby the difference between the received signal frequency and the local oscillator frequency of a superheterodyne receiver, increases with increasing signal frequency while maintaining the intermediate frequency constant.

25 A further object is to provide an improved form of superheterodyne receiver.

30 A feature of the invention relates to a superheterodyne circuit arrangement wherein the frequency difference between the received signal-modulated carrier and the local oscillator frequency can always be made higher than 50% of the signal frequency, regardless of what signal frequency is being received.

35 Another feature relates to circuit arrangements for the frequency conversion portion of a superheterodyne radio receiver, whereby the output of a local oscillator has its frequency automatically multiplied throughout the tuning range of the receiver.

40 A further feature relates to novel forms of tubes and circuit arrangements for use in superheterodyne receivers.

45 A still further feature relates to the novel organization, arrangement and relative interconnection of parts whereby there is provided a superheterodyne receiver having high translational or conversion gain over a wide range of received signal frequencies.

50 Other features and advantages not specifically enumerated will be apparent after a consideration of the following detailed descriptions and the appended claims.

55 In the drawing, Fig. 1 is a composite schematic circuit diagram explaining the fundamental concept of the invention.

60 Fig. 1a is a wave diagram to explain the functioning of the system of Fig. 1.

65 Figs. 2, 3, 4 and 5 represent respective modifications of Fig. 1.

70 Referring to Fig. 1, the numeral 1 represents diagrammatically an electron-discharge tube having an evacuated envelope enclosing a pair of electron-emitting cathodes 2, 3; a common grid 4; and a pair of anodes 5, 6, to receive electron-emission from the respective cathodes. The cathodes may be connected either within or outside the tube by a conductor 7.

75 Connected across the cathodes and the grid is a signal input circuit comprising a high frequency coupling transformer 8, the secondary of which is tunable to the signal frequency to be received, by means of variable condenser 9. A suitable grid biasing potential 10 may be interposed between the cathodes and grid. A tuned circuit, comprising the coil 11 and tunable condenser 12, is connected in push-pull relation across the anodes 5, 6. The midpoint of coil 11 is returned to the cathodes through the primary winding of a suitable intermediate frequency transformer, the primary 13 of which is bypassed by a high frequency by-pass condenser 14. Coupled to coil 11, for example by coil 15, is a local oscillator 16 preferably tunable as to frequency simultaneously with the tuning of the signal input circuit. In the usual way, the secondary 17 of the intermediate frequency transformer is tuned to the intermediate frequency by condenser 18.

80 Preferably, the inherent capacity between electrodes 4 and 5 is the same as the inherent capacity between electrodes 4 and 6. Assuming the local oscillations from source 16 are of a frequency f_L and are applied to the anodes 5 and 60

6, then because of the full-wave rectifying action in tube 1, current in conductor 19 will consist not only of a D. C. component but also of a high frequency component as shown in the cross-lined 5 portions of Fig. 1. The frequency of this component will be $2F_L$. When the received signal frequency in the form of a modulated carrier wave is applied to transformer 8, it will control the magnitude of current flowing from the cathodes to electrodes 5 and 6 thus controlling the amplitude of the current in conductor 19. Consequently, as indicated in Fig. 1a, a received signal (F_s) on grid 4 will in conjunction with the F_L frequency from source 16, give rise to a current 10 in conductor 19 of $(2F_L - F_s)$. Preferably, the frequency F_L will be chosen so that $F_s > 2F_L$ and therefore the resulting signal will be $(F_s - 2F_L)$ kc./sec. and consequently the difference between the received signal frequency and the local oscillator frequency is greater than 50% of the received signal frequency. For example, if, as assumed above, the system is to receive signal frequencies at one setting of 3000 kc./sec. and of 30,000 kc./sec. at another setting, with an intermediate frequency of 450 kc./sec., then at 3000 kc., with the arrangement described, the difference between the local oscillator frequency and signal frequency is 3000 kc. - 1275 kc. or 57.5% of the signal frequency. At the 30,000 kc./sec. setting, 20 it would be 30,000 - 14,775 or 50.75% of the signal frequency.

In the embodiment of Fig. 2, the received signal (F_s) is applied to the tunable oscillation circuit 21, 22, tuned to frequency F_s . This signal is 25 applied to grids 23, 24, of respective tubes 25, 26. The second grids 27, 28, of these tubes are connected in push-pull relation to the local oscillation circuit 29, 30, which is tuned to the local oscillator frequency F_L . This local frequency is 30 generated in the well known manner by feed-back action through coil 30 from the plate circuits of the respective tubes, by a feed-back coil 31, the D. C. operating potential 32 for plates 33, 34, being applied at the midpoint of coil 30. Because of the push-pull connection of grids 27, 28, the current in cathode conductor 35 has a component of frequency to $2F_L$. Likewise conductor 35 also carries component of frequency $F_s - 2F_L$ to which difference frequency primary 36 of the intermediate frequency transformer 37 is tuned by 35 means of condenser 38. The secondary of transformer 37 is connected to a suitable intermediate frequency amplifier of known construction. The grids 23 and 24 may be biased by the resistor 39 and shunt condenser 40 in the usual manner. It will be obvious that instead of mounting the various electrode sets in separate envelopes as in Fig. 2, they may be mounted in a common envelope. Such an arrangement is shown in Fig. 3 40 and the parts of Fig. 3 corresponding to those of Fig. 2 are designated by the same numerals. It is believed that the manner of operation of the system of Fig. 3 will be clear from the above description of Fig. 2.

Fig. 4 is a modification of the arrangement of Fig. 2. In Fig. 4 the triode tube 41 generates the local frequency F_L by means of feed-back coils 42, 43 respectively connected in the plate and grid circuits of tube 41; the tunable circuit 43, 44, being tuned to the frequency F_L . The incoming signal frequency F_s in the form of a modulated carrier wave is applied across the grid

45 and the cathode 46 of tube 47 which has two separate anodes 48, 49. The signal frequency F_s is amplified in tube 47 and by reason of the push-pull connection of anodes 48, 49 with the coil 50, the local frequency F_L is doubled to $2F_L$ and is superimposed on the circuit containing primary winding 50 of the intermediate frequency transformer thus producing the intermediate frequency $F_s - 2F_L$.

Fig. 5 is a further modification of Fig. 2, wherein in the tube 51 is provided with a cathode 52, a first grid 53, two separate second grids 54, 55, and an anode 56 common to the grids 54, 55, to the grid 53 and to the cathode 52. Associated with the cathode to receive emission from one section only thereof, is an anode 57 and a grid 58. The elements 52, 57, 58, constitute the local oscillator for generating the frequency F_L . In one particular superheterodyne receiver in which the tube and circuits of Fig. 5 were used, the incoming signal coil 59 was wound to cover the frequency band 2.46-7 megacycles using one section 60 of a 3-gang tuning condenser. A small trimmer condenser 61 was connected in the usual way in parallel with condenser 60. The intermediate frequency transformer 62 was tuned for a frequency of 460 kc., thus the tuning range for the local oscillator circuit 63, 64, 65, could be from $(2.46 - 0.46)/2 = 1.0$ m. c. to $(7 - 0.46)/2 = 3.27$ m. c. The tuning capacity consists of the two sections 64, 65 of the 3-gang condenser referred to above, the common operating mechanism of which is indicated by the dotted connections. The two sections 64, 65, actually form a split stator condenser and since capacities 60, 64 and 65 are all of the same value, the available tuning capacity for the oscillator circuit is only one half of the available tuning capacity in the signal circuit 59, 60. The usual trimmer condensers 66, 67, are connected in shunt to 64, 65.

The grid 58 of the local oscillator is directly connected to the grid 55 which in conjunction with grid 54 and cathode 52 doubles the frequency of the local oscillations. Thus, there is delivered to the primary winding of the intermediate frequency transformer 62 a frequency $F_s - 2F_L$. The grid 53 is preferably negatively biased to cathode 52 by the usual bias resistor 68 and shunt capacity 69.

While certain specific embodiments have been described herein, it will be understood that various changes and modifications may be made therein without departing from the spirit and scope of the invention.

What is claimed is:

A superheterodyne radio receiver including a tube containing a cathode, an anode to receive emission from one section of said cathode, a control grid adjacent said section of the cathode, a pair of auxiliary grids between said control grid and the anode, another anode adjacent a different section of the cathode, a control grid for said other anode, means to couple the second mentioned anode and the second mentioned control grid to generate a local frequency F_L , means to impress said frequency in push-pull relation across said pair of auxiliary grids, and means to impress received signal modulated carrier waves on the first mentioned control grid where-by there exists in the anode circuit of the first mentioned anode a current of frequency $F_s - 2F_L$.
